UNITED STATES PATENT OFFICE.

ALFRED A. DENNIS, OF GRAND RAPIDS, MICHIGAN.

PHONOGRAPH SOUND-BOX.

1,393,434.

Specification of Letters Patent. Patented Oct. 11, 1921.

Application filed June 21, 1920. Serial No. 390,352.

To all whom it may concern:

Be it known that I, ALFRED A. DENNIS, a citizen of the United States of America, residing at Grand Rapids, in the county of Kent and State of Michigan, have invented certain new and useful Improvements in Phonograph Sound-Boxes; and I do hereby declare the following to be a full, clear, and exact description of the invention, such as will enable others skilled in the art to which it appertains to make and use the same.

This invention relates to sound boxes such as are used with phonographs. The usual sound box includes a diaphragm which is vibrated by a stylus in turn operatively associated with the needle which traverses the record, the vibration of the diaphragm giving off sound waves which are carried to and amplified in any suitable amplifying horn or the like. It is an object and purpose of my invention to associate a means in connection with said vibrating diaphragm which will serve to, in a measure, modify the action of the same and change the character of the sound waves given off, resulting in better tone with an elimination of mechanical sounds and twangs which are usually present, a softer yet fuller tone being produced. A further object of the invention is to provide means for differently influencing the action of the diaphragm, so that the same may be changed for the reproduction of instrumental selections alone and likewise for the reproduction of vocal and instrumental combined. This is desirable as vocal reproduction is quite different from instrumental reproduction on phonographs. A further object of the invention is to make a sound box or reproducer having the improvements stated at a very low additional cost over sound boxes not so equipped. Many other objects and purposes will appear fully and in detail as understanding of the invention is had from the following description, taken in connection with the accompanying drawing, in which,

Figure 1 is a plan view of a sound box or reproducer equipped with my invention, and

Fig. 2 is a central vertical section therethrough.

Like reference characters refer to like parts in the different figures of the drawing.

The sound box casing 1 is of the usual construction and is attached at the end of the tone arm 2. A thin diaphragm 3 is permanently secured in the casing 1, any suit-

able means of securing the same being used. A relatively heavy coiled spring 4 is connected at one end to the center of the diaphragm by means of a screw 5 which also may serve to attach the stylus 6 to the diaphragm, said stylus being equipped with the usual needle holder 7 in which the needle for traversing the records is held.

Spring 4 extends into the tone arm for a distance. A bar 8 having a downturned end 8^a is mounted within and at the upper side of the tone arm, its downturned end carrying a head 9 which is adapted to engage with the free end of spring 4 when moved to one position. To mount the bar 8 a short rod 10 is attached thereto and passed through a slot 11 in the upper side of the tone arm 2, being equipped with an operating knob or handle 12 at its upper end and carrying a friction leaf spring 13 disposed between the handle 12 and a plate 14 fastened to the upper side of the tone arm and likewise slotted for the passage of rod 10. A pointer 15 is made integral with the spring 13 and is used to indicate the positions to which the device should be moved, plate 14 carrying two indicating characters, one, "I" and the other "V I," indicating instrumental and the combination of vocal and instrumental. When the pointer points to the character "I," head 9 is free of the end of spring 4, but when the pointer points to the characters "V I," said head bears against the free end of the spring and compresses it to a slight degree. The end of the slot toward the sound box limits the extent of movement of the head 9 which can not be too much as too great pressure against the spring transmitted to the diaphragm will substantially check vibration and mute the tones.

When the spring hangs free on the diaphragm, the weight thereof serves to modify the action of the diaphragm and its effect with instrumental pieces is to eliminate the harsh blare that usually accompanies the reproduction and also there is a practical elimination of the metallic sound coming from over vibration of the amplifying horn when the same contains metal either in whole or part. The spring should be free for purely instrumental records, in which case the tone is very markedly benefited. For vocal pieces and those accompanied by instruments, said instrumental parts being subordinate to the vocal, the head 9 should be moved into contact with the spring and compress it slightly.

This carries the weight of the spring between the diaphragm and head 9, and the stiffening of the diaphragm which comes from the free weight of the spring acting thereon is to a great extent obviated, while the spring itself vibrates with the diaphragm, being flexible and capable of vibration, bring the vocal tones out clearer and fuller; while any instrumental tones are not unduly enlarged and amplified. The pressure of the spring may be made greater or less as desired by moving the head more or less against the spring, the leaf spring 13 holding the device at any place to which it is moved, though too great pressure on the spring 4 cannot be made as the rod 10 is limited in movement by the end of the slot 11. The invention has received practical test and proven its value, irrespective of whether or not the theory advanced above may be true and exact.

The invention is capable of embodiment in various forms of construction, and I, accordingly, do not wish to be limited to the exact structure shown and described, but consider myself entitled to all forms of construction coming within the scope of the appended claims defining the invention.

I claim:

- 30 1. In a phonograph sound box or reproducer, a casing, a diaphragm mounted in the casing, and a relatively heavy wire coil attached to the rear side of the diaphragm and extending therefrom, substantially as described.
- 35 2. In a phonograph sound box or reproducer, a casing, a diaphragm mounted on the casing, a relatively heavy spring coil attached to the rear side of the diaphragm and extending therefrom, and means adjustably mounted to engage with the free end of the spring or move away therefrom to leave said end of the spring free, substantially as described.
- 40 3. In a phonograph sound box or reproducer, a casing, a diaphragm mounted on the casing, a relatively heavy coiled spring attached to and extending from the rear side of the diaphragm, means adjustably mounted at the free end of the spring and operable into and out of engagement with the same, and means for operating said means manually, substantially as described.

4. In a sound box or reproducer, a reproducer casing and diaphragm therein, a tone arm on the end of which the casing is mounted, a relatively heavy coiled spring attached to the rear side of the diaphragm and extending into the tone arm, and means adjustably mounted on the tone arm adjacent the free end of the spring and operable into and out of engagement therewith, said means when engaged with the spring slightly compressing the same, substantially as described.

5. In a phonograph sound box or reproducer, the combination of the reproducer casing and diaphragm therein, of a relatively heavy coiled spring attached to the rear side of the diaphragm, a tone arm to the end of which the casing is attached and into which the spring extends, means adjustably mounted on the tone arm adjacent the free end of the spring and operable into and out of engagement therewith, and means attached to said adjustable means and manually operable from outside the tone arm for moving said adjustable means into and out of engagement with the spring, substantially as described.

6. In a phonograph sound box or reproducer, the combination of the reproducer casing and diaphragm therein, of a relatively heavy coiled spring attached to the rear side of the diaphragm, a tone arm to the end of which the casing is attached and into which the spring extends, a bar mounted within the tone arm and provided with a head disposed adjacent the free end of the spring, means for slidably mounting said bar on the arm to bring the head into engagement with the free end of the spring or to carry said head away from the spring, and means for operating said bar in its movements from without the tone arm, substantially as described.

7. The combination of elements defined in claim 6 combined with yielding means for retaining the bar in any position to which it is moved, substantially as described.

8. The combination of elements defined in claim 5, combined with means for yieldingly holding the said adjustable means in positions to which it may be moved, substantially as described.

In testimony whereof I affix my signature. 105
ALFRED A. DENNIS.
